UNITED STATES PATENT OFFICE.

FREDERICK H. DUNLAP, OF GIRARD, OHIO.

MACHINE FOR SEALING ENVELOPS.

No. 861,955.

Specification of Letters Patent.

Patented July 30, 1907.

Application filed June 27, 1906. Serial No. 323,602.

To all whom it may concern:

Be it known that I, FREDERICK H. DUNLAP, a citizen of the United States, residing at Girard, in the county of Trumbull, State of Ohio, have invented certain new and useful Improvements in Machines for Sealing Envelops; and I do hereby declare the following to be a full, clear, and exact description of the invention, such as will enable others skilled in the art to which it appertains to make and use the same.

10 This invention relates to envelop sealing machines, and the object thereof is to improve the construction of the moistening and carrying rollers and of the flap folder.

With this end in view, the invention consists in the 15 construction, combination and arrangement of parts, all as hereinafter fully described and illustrated in the accompanying drawings, in which—

Figure 1 is a plan view with the cover of the casing removed. Fig. 2 is a horizontal sectional view of the 20 device with the table removed. Fig. 3 is a longitudinal vertical section on the line 4—4 of Fig. 1. Fig. 4 is a similar view on the line 3—3 of Fig. 1. Fig. 5 is a side view showing the arrangement of the gears for 25 rotating the various rolls. Fig. 6 is a perspective view of the folding device.

Like parts are designated by corresponding numerals in the several views.

Referring to the drawings, the machine will be seen to be inclosed by a casing consisting of a top or cover 30 10, and side pieces 11 and 12 connected thereto. Located in said frame and extending a slight distance beyond each end thereof, is a receiving table 13 having supporting feet and provided with a front section 14, there being a slight space between the table proper 35 and its section, as shown in Fig. 3, into which extend a pair of carrying rollers 15 and 16 mounted upon shafts 17 and 18 journaled in the sides of the frame.

The space between the sides is sufficiently great to 40 permit an envelop of practically any size to be sent through the machine at the forward part thereof with its flap extended or open, as shown in Fig. 1, and the front carrying rolls are of approximately the same length.

The upper carrying roll 15 is formed with a reduced 45 outer end 19 around which is fastened a layer of felt or other suitable moisture absorbent material, which is kept in a dampened or wet condition by means of a receptacle 21 carried upon the adjacent side of the frame and provided with an opening through which 50 the liquid falls upon said pad.

As stated above, the front carrying rolls are of approximately the same length as the width of the frame while the intermediate carrying rolls 22 and 23 of which four pair are shown, are approximately only one-third 55 as long as the front rollers. The rolls of the several

pair are located on opposite sides of the table 13 one above the other, as shown, and the lower rolls 23 extend slightly above the upper face of said table through transverse slots 24 provided for that purpose.

The upper rollers are mounted upon shafts 25, the outer ends of which are journaled in the frame side 12, while the inner ends are carried by hangers 26 attached to the under face of the frame top.

The outer ends of the carrying rollers 22, and the front moistening roll 15 are provided with gears 27 mounted thereon exterior of the side 12, there being a series of idlers 28 mounted on pins on said side, one idler being in mesh between each adjacent pair of gears 27 whereby the several rolls will be rotated in the same direction.

70 The outer ends of the carrying rolls 23 which are of the same length as rolls 22 are mounted on shafts 29 which, however, extend entirely across said frame and carry on their outer ends gears 30, mounted exterior of side 11 which is provided in like manner with a series of 75 idlers 31.

It will be seen that when an envelop 32 is sent through the front portion of the machine with its flap open, the flap will be moistened by the action of the pad upon the front roll 15, but that owing to the 80 formation of the inner carrying rolls 22, the moistened flap will be untouched by said rolls as the envelop passes thereunder.

Located in close proximity to the outer end of the rearmost carrying roll 22 is the folding device 33, consisting of a single strip of metal bent, as shown in Fig. 6, into funnel shape, the larger opening being directed towards the front of the machine. Owing to the curved formation of the folder, the moistened flap of an envelop in its passage through the machine will 90 contact with the inclined side of the holder, and will be folded over and closed upon the body of the envelop.

Located adjacent the rear end of said folder is a pair of sealing rollers 34 and 35 situated above and below 95 the receiving table and extending into a transverse slot 36' therein, in like manner with the front rolls 15 and 16.

Journaled in the rear of the sealing rolls, are the 100 shafts 36 and 37 by means of which motion is transmitted from the lower gears 30 to the upper gears 27 on the opposite side of the machine. To this end the upper shaft is provided at its ends with gears 38, one of which is in mesh with the rearmost gear 30 of the lower rolls while at its opposite end the gear 38 thereon will mesh with the idler 28 which in turn meshes with the rearmost gear 27 of the upper rolls.

105 The rotation of shaft 37 is effected preferably through a gear 37' mounted thereon on the end opposite to that which carries the gear 30, the gear 37' being in 110

mesh with and driven by a gear 38' on the shaft 39' of an engine (not shown). If desired, however, a crank handle may be substituted for the gear 37' to permit shaft 37 to be manually rotated.

5 The folding device is adjustably positioned upon the table 13 by means of a set screw 39 passing through a perforation in said folder and through a transverse slot 40 in the table, the lower end of said set screw carrying a nut 41 by means of which said folder is retained in its adjusted position.

10 The shafts of the various rolls have a yielding movement with respect to each other, owing to the provision of coil springs 42 between the journal boxes 43 in which said shafts are mounted in the respective sides 15 of the frame.

Owing to the yielding relation of the rolls of each pair, it will be possible for envelopes of various degrees of thickness to be sent through the machine without being unduly squeezed or otherwise injured.

20 The reduced end 19 of the front roll 15 is of sufficient length to permit pads of various widths to be attached thereto so that only the envelop flap may be moistened and that various sizes of envelopes may be used.

Owing to the provision of the short carrying rolls, 25 22 and 23, the moistened flap will not contact with the surface thereof, while the envelop will still be sufficiently supported and gripped between said rolls to pass it forward along the receiving table through the folder and into position to be seized by the sealing rollers 35 and 34 and the flap evenly pressed down upon the body of the envelop.

The front section 14 of the table extends a sufficient distance around the front end of the machine to form a clear feeding space for the envelopes and 35 the rear end of the table in like manner extends beyond the rear end of the machine.

It will be readily understood that letters of practi-

cally any size or thickness, may be sealed by the machine.

The operation of the machine will be readily understood from the above and further description thereof is thought to be unnecessary.

Modifications and changes may be made within the scope of the claims and without departing from the spirit of the invention, which is therefore not intended to be limited to the exact construction as shown and described.

What is claimed, is:—

An envelop sealing machine comprising in combination a transversely slotted receiving table; a frame inclosing said table; a pair of carrying rolls journaled at the front end of the table on opposite sides thereof and extending into the slots therein; the outer end of the upper roll having a moistening pad attached thereto; means for supplying liquid to said pad; a series of depending hangers secured to the frame top; a series of upper carrying rolls having their outer ends journaled in one of the frame sides and their inner ends journaled in said hangers; a series of lower carrying rolls disposed beneath said upper rolls, and extending into the slots in the table, the length of each of said upper and lower carrying rolls being less than the width of the sealed envelop; a folding device adjustably mounted upon the upper face of said table adjacent the inner end of the rearmost roller of said upper series, in position to engage and close the flap of an envelop engaged by said rolls; a pair of sealing and pressing rolls mounted in opposite sides of the table in the rear of said carrying rolls, the rear end of said folder extending partway between said rolls; means for yieldably supporting the rolls of the several pairs with respect to each other; and means for rotating the same in the same direction.

In testimony whereof, I affix my signature, in presence of two witnesses.

FREDERICK H. DUNLAP.
